(57) CLAIM

The ornamental design for a shoe upper, as shown and described.

DESCRIPTION

FIG. 1 is a top perspective view of the shoe upper from the lateral side;

FIG. 2 is a front view thereof;

FIG. 3 is a rear view thereof;

FIG. 4 is a medial side view thereof;

FIG. 5 is lateral side view thereof;

FIG. 6 is a top view thereof; and,

FIG. 7 is a bottom view thereof.
